APPARATUS FOR MINING COAL

Walter Vogel, Santiago de Chile, assignor
to Mavor & Coulson, Limited, Glasgow S. E.,
Scotland

Application December 23, 1948, Serial No. 66,877
In Great Britain July 7, 1947

3 Claims. (Cl. 262—8)

1

This invention relates to a method of mining coal and other minerals and to a mining machine of a previously proposed type in use of which cutting of the coal or other mineral is effected by a direct shearing or chisel-like action applied by a wedge-like cutter in a horizontal direction and in a plane behind and parallel to the face of the seam so as to wedge the mineral away in blocks from the seam.

More particularly, the invention relates to a method of mining coal or other mineral which consists in wedging out from a seam the mineral located between one of the limits (namely the roof and the floor) of the seam and an intermediate level, and thereafter wedging off the mineral left outstanding between said level and the other limit of the seam.

The mineral between the roof and an intermediate level may be wedged out first.

The intermediate level may be about midway between the roof and the floor.

The present invention comprises a mining machine of the type stated having alternately movable wedge-like cutters one of which is adapted to be driven a stroke forward so as to wedge out a section of the face of a mineral seam between one limit thereof and an intermediate level while the other cutter is anchored, and the other cutter is adapted to be driven a stroke forward so as to wedge off the mineral left outstanding on the face between said level and the other limit of the face.

Preferably, it is the upper wedge-like cutter that comes into action first so as to wedge out the mineral between the roof and an intermediate level.

A machine according to the invention is shown as an example in the accompanying drawings, in which Fig. 1 is an elevation of the machine, the hydraulic piping being omitted for clearness.

Fig. 2 is an end elevation of the machine as seen in the direction of the arrow 2 in Fig. 1, Fig. 2 showing parts differently positioned.

Fig. 3 is a plan of the machine, the view being partly a section approximately on the line 3—3 of Fig. 1.

Fig. 4 is a diagrammatic elevation illustrating the hydraulic apparatus with which the machine is equipped.

In the example shown, the invention is applied to a double-ended coal-mining machine; that is, a machine adapted to cut in either of its two directions of travel along the face of a coal seam. The machine is in the nature of a vehicle which is movable forward stroke-after-stroke and which comprises two components 5 and 6

2

(Fig. 1) that are movable lengthwise, each in relation to the other. The component 5 is constructed in two interconnected main parts at opposite ends of the machine, and the component 6 occupies an intermediate position. The means of connection between the opposite end parts of the component 5 are main and auxiliary bars 5A and 5B; and the component 6 is slidably mounted on these bars, which function as guides for the component 6.

Each of the components of the machine incorporates one of the two elements of a hydraulic cylinder-and-ram unit for the propulsion of the vehicle. In the example, the component 5 incorporates the ram 7 and the component 6 incorporates the cylinder 8. The hydraulic unit is powerful enough to perform the double function of advancing either of the components of the vehicle and at the same time shearing off the coal.

20 In the drawings, A indicates the floor of the mine, B indicates the roof, C indicates the face of the seam of coal to be cut and D indicates the newly cut face.

The component 5 has two hydraulic jacks 9 and 10, one on each of two cutter heads 11 and 12 incorporated in the component 5 at opposite ends. A more powerful hydraulic jack 13 is provided on the component 6 in combination with the propulsion cylinder 8.

25 The cutter heads 11 and 12 are each made chiefly as a large wedge-form cutter presenting an inclined edge 14 which extends in a vertical plane from floor level to a level which may be about half the height of the coal face. This lower cutter 14 is combined with a ramp 15 presenting an upwardly and outwardly inclined surface for the passage of broken-down coal to a conveyor (not shown, but located at the side of the machine opposite to the coal face C, D). The component 6 carries two upper wedge-form cutters 16 and 17 respectively, at opposite ends of long beams 18 and 19. Each upper cutter presents an inclined edge 20 which extends in a vertical plane from roof level to or about the previously mentioned intermediate level. The beams 18, 19 are movable about the horizontal axes of pivot pins 21 on brackets 22 forming parts of the same structure as the component 6 with its propulsion cylinder 8 and jack 13. These beams 18, 19 have top plates 18A and 19A respectively, which are slotted for passage through them of the jacks 9 and 10; see the slot 19B in Fig. 3. The beams 18, 19 are pivotable in a vertical plane so as to bring that cutter 16 or 17 which is at the front for the time

30 35 40 45 50 55 being into engagement with the roof B. The cut-

ter heads also have auxiliary hydraulic jacks 23 and 24, respectively, for pressing the leading upper cutter 16 or 17 against the roof. The rams of these jacks have rollers 23A and 24A by which the upward pressure is transmitted to the beams.

The upper and lower cutters are arranged so that their edges 14 and 20 cut in the same vertical plane, which is represented in Fig. 2 by the newly cut face D. This plane is behind and parallel to the original coal face C. The cutters are also made to strip off coal from the floor A and roof B. As shown, the lower cutter heads each have horizontally edged cutting portions 25 to strip the floor, and the upper cutters each have a horizontally edged cutting portion 26 to strip the roof.

The hydraulic apparatus incorporated in the machine comprises the propulsion unit 7, 8 and the five jacks 9, 10, 13, 23 and 24. These hydraulic devices are all under the control of a manually operated distributor valve 27, which like the remainder of the hydraulic system is represented symbolically in Fig. 4. The system also includes a supply tank 28 to and from which circulates the hydraulic liquid (usually oil), a hydraulic pump 29 which draws from the tank 28 and discharges to the valve 27 through pipes 30. These parts 27 to 29 are all provided on the component 5. The system also includes pairs of pipes extending between the valve 27 and opposite ends of the cylinders of the hydraulic devices. As shown, these pipes comprise the following pairs: pipes 31 to the propulsion unit cylinder 8, pipes 32 to the jacks 9 and 10, pipes 33 to the jack 13 and pipes 34 to the jacks 23, 24.

As shown, the cutters 11 and 16 are in front, the machine being set to work from left to right of Figs. 1, 3 and 4.

In operation, assume that the component 5 is fully advanced and is anchored between roof and floor by its jacks 9 and 10. The jack 13 of the other component 6 is retracted so that this component is free to advance. The valve 27 is manipulated so that the hydraulic propulsion unit is operated to extend, that is so as to advance the component 6 a stroke forward, with which the front upper cutter 16 also advances and wedges out coal from the upper half of the seam. Fig. 1 shows the machine at this stage, namely with the component 6 fully advanced. Next, the valve 27 is manipulated so that the jack 13 is operated to anchor the component 6, and also so that the jacks 9, 10 of the component 5 are retracted to free it, and thereafter so that the hydraulic unit 7, 8 is operated to advance the other component 5 a stroke forward. Thus, the front lower cutter 11 is advanced to wedge off from the lower half of the seam the coal left outstanding like a ledge. In the advance of the front lower cutter, the broken down coal is displaced sidewise and upwards by the ramp 15. Thereafter, the

valve 27 is operated so that the jacks 9, 10 of the component 6 are operated to anchor it and so that the jack 13 of the other component 6 is retracted to free it; and the cycle of operations is repeated step-by-step.

Any of various modifications may be made. For instance, the prior cutting of coal between the roof (or the floor) and an intermediate level, being the cut which involves the heavier work, may be done by means of a cutter comprising a number of cutting tools working at progressively greater depths into the coal face.

I claim:

1. A mining machine consisting of a vehicle which is movable stroke-after-stroke and which comprises two components, interengaging longitudinal guides on said components, by virtue of which guides each one of said components is movable longitudinally forward relative to the other, an upper wedge-like cutter provided on one of said components and arranged to wedge out mineral from a seam between the top thereof and an intermediate level, a lower wedge-like cutter provided on the other of said components and arranged to wedge off the remaining mineral from the seam between the bottom thereof and the intermediate level, jacks on the individual components for anchoring them alternatively, a propulsion unit interconnecting the two components, and means controlling the operation of said jacks and said unit so that each component in its turn is anchored by its jack while said unit operates the other component to make a stroke forward and perform its wedge action on the seam.

2. A mining machine as claimed by claim 1 in which the upper wedge-like cutter extends in front of the lower wedge-like cutter so that the mineral between the top of the seam and an intermediate level is wedged out before the lower mineral is wedged off.

3. A mining machine as claimed by claim 2 in which the upper wedge-like cutter is carried by a beam extending from the appropriate one of said components and in which a device forces the beam upwards to bring said cutter to the top of the seam throughout each forward stroke of said cutter.
